UNITED STATES PATENT OFFICE.

JOHN PRIMROSE, OF NEW YORK, N. Y., ASSIGNOR TO POWER SPECIALTY COMPANY, OF NEW YORK, N. Y., A CORPORATION OF NEW YORK.

OIL STILL.

Application filed July 2, 1921. Serial No. 482,185.

To all whom it may concern:

Be it known that I, JOHN PRIMROSE, a citizen of the United States of America, residing at New York, in the county and 5 State of New York, have invented certain new and useful Improvements in Oil Stills, of which the following is a full, clear, and exact description.

In certain forms of cracking still now 10 well known and largely used, it is usual to build the furnace with a dividing partition or wall of refractory material between the fire chamber and the bank of tubes through which the oil flows. The hot gases of combustion in such cases pass from the fire chamber over the bridge wall and sweep down over the oil tubes on their way to the flue. This is a general description of a 15 typical form of still, but for purposes of the present application it will suffice to indicate the general form of apparatus to which the invention subject of this application is designed for use.

In stills of this character it has been 20 found necessary to maintain a relatively low furnace temperature, for example about 1400°, for obtaining the best results in distillation, but this involves the use of a large excess volume of air, and in consequence a 25 somewhat low fuel economy. Efforts to cut down the amount of fuel and to raise the furnace temperature have not been satisfactory, as in such event the top row of oil tubes became overheated, because although 30 the oil was passing through them at a very high rate, it did not carry off the heat absorbed at a rate which would keep the temperature of the metal of the heating surface 35 below the burning point. It also resulted in a violent heating of the oil at this point, bringing about a deposit of carbon on the 40 inside of the tubes too great to permit of long continued operation.

A careful study of these facts and conditions led me to believe that the main obstacle to the economical use of this type of still lay in the fact that the refractory roof wall of the furnace became very highly heated and radiated this heat directly upon 45 the upper row of oil tubes, and that this radiant heat was the limiting feature, which operated as an insuperable obstacle to the efficient operation of such stills so long as it was present. I therefore sought to remove its cause and consequently its effect,

and having once succeeded in doing this I found that a great gain in economy and efficiency was at once secured.

This invention therefore resides primarily in eliminating to as great a degree as is practicable and possible, the effect upon the oil tubes of a still, of direct radiant heat, whereby the heating will be accomplished by convection, and the most feasible means that I have devised for accomplishing this is to establish as far as practicable opposing heating or heat absorbing surfaces instead of a heat radiating and a heat absorbing surface.

For this purpose I construct the furnace in the usual manner with a fire chamber and a tube containing chamber into which the hot gases flow after passing over the top of the bridge wall. The roof of the fire chamber may be of refractory brick, but that of the other chamber immediately above the bank of tubes is composed chiefly of oil tubes exposed directly to the furnace gases. These tubes are advantageously carried across the roof of the fire chamber where they are protected by refractory blocks or bricks. These latter are relatively poor conductors of heat and are also kept at a fairly low temperature by the oil tubes within them.

The exposed tubes, however, over the bank of tubes, with which they are connected in series, do not radiate as much heat, but absorb it, and I have found that when this provision is made for reducing the amount of heat that would otherwise be radiated directly from the roof onto the bank of tubes, that a very great advantage is gained.

Of course heat will be radiated to some extent from the side walls of the tube chamber, but this radiates at an angle to the tubes and not directly upon them, and its effect is much less serious. The main disturbing cause, the direct radiation of heat from the roof, is practically eliminated.

The nature and principle of this invention are such as to make it of much wider application than to the mere protection of the tubes of an oil still. For example, the same plan is of great value and importance in the case of any kind of fluid heater in which the medium to be heated is not capable of carrying off the heat as rapidly as the heating surface absorbs it by radiation. This applies, for example, to independently

fired superheaters, or to gas heaters, or to other like devices in which the heating surface absorbs the heat direct from the furnace. It is, of course, a matter of common knowledge that the heat is absorbed by radiation at a much higher rate than by convection.

I have illustrated my improvement in the accompanying drawing as applied to an oil still, the said drawing being a vertical sectional view of any ordinary form of still having the general characteristics hereinbefore described.

The furnace walls 1 are of the usual character and material, and a bridge wall 2 is built up to divide the furnace into two chambers communicating over the top of the said wall. The source of heat may be a coal fire or fuel oil.

20 The roof of the fire chamber is composed partly or wholly of refractory blocks 3, through which pass oil tubes 4 placed at a suitable distance apart. The roof of the tube chamber is composed of exposed tubes 25 4, and these also are placed as close together as structural conditions will permit.

Below in the tube chamber is arranged a bank of tubes 5 connected in any suitable manner, but preferably so that the flow of oil will be counter to the flow of hot gases. The roof tubes 4 are connected in series with those of the bank 5, and all tubes 5 exposed to the hot gases are preferably of steel encased in corrugated rings of cast iron. The 35 portion of the roof tubes 4 directly over and opposing the tube bank 5 are preferably provided with plain cast iron coverings or casings 7. Such coverings are not essential as bare tubes may be used as well.

40 Beneath the bank of tubes is a damper 6, and otherwise the apparatus is supplied with the usual and well known accessories.

If the roof of the tube chamber were of some refractory material it would become highly heated and radiate its heat directly upon the upper row of tubes of the bank 5, and this, as pointed out above, will result in overheating the top row of tubes. As constructed, however, the roof of the tube chamber absorbs rather than radiates heat, in the same way as the upper row of tubes of the bank by contact with the hot gases only. Hence, as the opposing heating surfaces are at substantially the same temperature, there is no appreciable interchange of heat between them by radiation.

The so-called bridge wall 2 protects the tubes 5 from the direct radiant heat of the fire chamber of the furnace. The hot gases of combustion are directed from the furnace directly between the two banks of heating surfaces 4 and 5. Under these conditions the upper row of tubes in bank 5 are exposed to the hottest gases and would tend to become highly heated. If the opposed heat-

ing surfaces 4 were omitted the opposing wall in opposition to the surfaces 5 would become highly radiant and this radiant heat would act cumulatively with the heat of convection of the hot gases upon the uppermost tube row in 5 and these upper tubes would be overheated thereby overheating the oil therein and necessitating frequent tube replacements. By providing the opposed heating surface 4, I not only prevent radiation from hot brickwork but also prevent interchange of heat by radiation between the heating surfaces 4 and 5. Furthermore, there is a useful recovery of the heat in the oil passing through the pipes 4. In effect, the upper heating surface provides a so-called dark spot in opposition to the heating surfaces 5.

In heaters it is desirable that the heat absorbing surfaces should be so disposed with relation to source of heat that every unit area of the surface should absorb heat at a uniform rate. Such results are not entirely obtainable but the arrangement of opposed surfaces heretofore described more nearly approaches the desired condition than those heretofore proposed. In the present construction the absorption rate of the surfaces nearest the heated furnace and exposed to the hottest gases has been reduced and consequently higher gas temperatures are secured further on in the heater thereby causing a higher heat absorption at such points.

This construction has been found to completely eliminate the objection to stills and other devices of this general character and type, and permits a much higher furnace temperature without injury to the oil, steam or other similar tubes.

The method of treating oil by the apparatus herein claimed is not claimed in the present application but is claimed in my copending application, Serial No. 611,932, filed January 11, 1923.

What I claim as my invention is:

1. An oil heater comprising a fire chamber in which intense radiant heat is developed and a tube chamber, a heat absorbing surface in said tube chamber, an intermediate refractory wall between the tube chamber and the fire chamber and a roof for the tube chamber composed of heat absorbing surfaces disposed in opposition to the heat absorbing surface in the tube chamber whereby the last mentioned heat absorbing surfaces are protected against overheating by radiant heat.

2. An oil still comprising a furnace divided by a bridge wall into two compartments communicating over the top of said wall, one compartment being a fire chamber in which the heat of combustion develops intense radiant heat, a bank of tubes in the other chamber, a roof for the fire chamber

composed of oil pipes encased in refractory blocks, and a roof for the tube chamber composed of exposed oil pipes, the roof pipes being connected in series with those in the 5 bank.

3. In an apparatus of the kind described a furnace in which intense radiant heat is developed, a bank of tubes in position to be swept by the hot gases direct from the furnace, and an opposing wall of heat absorbing surface as distinguished from heat radiating material, whereby the exposed row of tubes in said bank will be protected from the direct radiation of heat from said opposing wall.

4. In an apparatus of the kind herein described, the combination with a furnace in which intense radiant heat is developed, of a heat absorbing surface screened from 20 the fire and divided into two opposing parts between which the heat of the furnace is directed, whereby no part of said heat absorbing surface will be exposed to direct heat rays from the fire or the furnace walls.

25 5. In a furnace, a combustion chamber in which intense radiant heat is developed, a heat absorption chamber in open communication therewith, fluid conveying means located in said heat absorption chamber, said 30 heat absorption chamber having wall portions in radiant heat receiving relation relative to said combustion chamber and in heat radiating relation to said fluid conveying means, and means upon said wall to prevent 35 such heat radiation.

6. An oil heating apparatus comprising in combination, means including a plurality of conduits through which the oil to be heated is passed, means including a high intensity source of heat for subjecting said 40 conduits to heat of convection, and means for preventing the destruction of the said conduits and the overheating of the oil therein by excessive radiant heat, said means comprising a heat-absorbing means interposed at a point out of the stream of hot 45 gases and cooperating with the aforesaid conduits to prevent a radiant heat interchange therewith.

50 7. An oil heating apparatus comprising in combination, with means including a plurality of conduits through which the oil to be heated is passed, means including a high intensity source of heat for subjecting said 55 conduits to heat of convection and means for preventing destruction of said conduits and the overheating of the oil therein by excessive radiant heat, said means including a non-radiant opposing surface located out 60 of the stream of hot gases from said source for protecting such of the aforesaid conduits which would otherwise be subject to destructive radiant heat.

65 8. An oil heating apparatus comprising means including a plurality of conduits

through which the oil is passed, means such as a high intensity source of heat for subjecting the oil in said conduits to heat of convection, means for protecting the oil in such of the conduits as would otherwise be exposed to destructive radiant heat and for usefully recovering heat from said source, said means including oil-containing heat-absorbing conduits in position to provide a relatively dark area in opposition to the aforesaid exposed conduits.

9. An oil heating apparatus comprising in combination with a plurality of conduits for the oil to be heated, means including a high intensity source of heat for heating oil in said conduits, and means for protecting such of the conduits and the oil contained therein against destruction and for usefully recovering heat from said source, said means including oil-containing heat-absorbing conduits positioned to provide a relatively dark area in opposition to such of the aforesaid conduits which would otherwise be subject to radiation.

10. In an apparatus of the kind described, a bank of tubes adapted to be swept by hot gases from a source developing intense radiant heat, an opposing wall therefor of heat-absorbing surface as distinguished from heat-radiating material, whereby the exposed row of tubes in said bank will be protected from direct radiation of heat from said opposing wall, means for conveying a medium to be heated first through the bank of tubes to impart an initial heating thereto, and thence through the last mentioned heat-absorbing surface to further heat the same.

11. In a device of the class described, in combination, a furnace having a fire chamber in which intense radiant heat is developed and a heat-absorption chamber, a heat-absorbing surface therein adapted to receive heat from the hot gases and heat up a medium conveyed therethrough, means for shielding portions of said surface from the direct heat of the fire chamber, and means for controlling and preventing an excessive heating of said surface by radiation from the chamber walls including a second heat-absorbing surface in opposition to and cooperating with the first mentioned heating surface to prevent either surface attaining an excessive temperature.

12. In an apparatus of the kind described, the combination with a furnace in which intense radiant heat is developed, of a heat-absorption chamber therein, of a heat-absorbing surface within said chamber, a second heat-absorbing surface disposed in opposition to the first surface, means for admitting the heated gases from the furnace directly between said surfaces, said surfaces cooperating with each other to absorb heat and to prevent high and destructive heat radiance in said chamber.

13. In an apparatus of the kind described, in combination, a heat-absorption chamber and a fire chamber in which intense radiant heat is developed, walls for said chambers, a heat-absorbing surface in the absorption chamber adapted to be swept by hot gases, a second heat-absorbing surface on the wall opposite the first heat-absorbing surface and adapted, by the absorption of heat thereby to prevent destructive radiation upon the first mentioned heating surface from said opposite wall, and means for directing gases from the fire chamber between the two heat-absorbing surfaces and for shielding other portions of the first heat-absorbing surface from the direct heat of the fire.
14. In an apparatus of the kind described, in combination, a source of heat adapted to develop intense radiant heat, means including a plurality of opposed heat absorbing surfaces with provisions for conveying successively therethrough a medium to be heated, said surfaces and heat absorbing medium cooperating by absorbing heat to prevent heat inter-change by radiation between said surfaces, and a protecting wall arranged to shield one of said surfaces from the direct heat of said source and to direct the hot gases from the source between the said surfaces.
15. In an apparatus of the kind described, a furnace in which intense radiant heat is developed, in combination with a plurality of banks of heating surfaces through which the medium to be heated flows, a wall screening one bank of heating surfaces from the direct radiant heat of the furnace chamber, but permitting hot gases to sweep said last mentioned bank, the other bank of heating surfaces being disposed in opposition to the screened surface to absorb heat and prevent radiation of heat to those surfaces of such screened surface which are exposed to the hottest furnace gases, whereby the gas temperatures may be increased and the heating surfaces of the screened surface subsequently traversed by the hot gases may absorb proportionally more heat.

In testimony whereof I hereto affix my signature.

JOHN PRIMROSE.
